UNITED STATES PATENT OFFICE.

AUGUST REHFELDT, OF DUISBURG, GERMANY.

IRONING HORSE FOR SLEEVES.

Application filed August 24, 1925, Serial No. 52,115, and in Germany September 3, 1924.

This invention relates to an ironing-horse for ironing smooth or puffy sleeves of wearing-apparel. According to the invention an angular ironing pad is oscillatably mounted on a base plate, so that, according to requirement, either one of the two arms of the pad may be brought into the position of use.

An embodiment of the invention is shown, by way of example, in the accompanying drawing in which—

Fig. 1 is a side elevation, and

Fig. 2 a plan view.

The ironing-horse for sleeves comprises an angular ironing pad a having two arms a' and a², the one arm a' being curved at its end. The cushion is oscillatably mounted on a base plate b on two lateral supports c so that it can be oscillated around an axle d in order to bring into the position of use either one of the two arms, according to requirement. A locking bolt or bolts e on the base plate serve to securely fix the adjusted arm in the position of use.

The top ends of the sleeves to be ironed are placed over the arm a' of the ironing pad, said arm being curved for this purpose, all the other portions of a lady's jacket being ironed on the arm a². Both arms a' and a² serve further as support if seams are to be tacked which up to the present has to be done by holding the garment on the hand.

I claim:—

An ironing-horse for sleeves comprising in combination a base plate, an ironing pad of angular shape, an axle oscillatably holding said pad on said base plate so that, according to requirement the one or other arm of the angular pad may be brought into the position of use, and a locking bolt for fixing the adjusted arms of the ironing pad in the position of use.

In testimony whereof I affix my signature.

AUGUST REHFELDT.
